INVENTOR-
Vencent G. Apple

UNITED STATES PATENT OFFICE

VINCENT G. APPLE, OF DAYTON, OHIO

DYNAMO-ELECTRIC MACHINE WITH IMPROVED COOLING MEANS

Application filed April 30, 1930. Serial No. 448,646.

This invention relates to dynamo electric machines and particularly to such as are compelled to carry a large percentage of over-load resulting in an inordinate amount of heat being generated.

The object of the invention is to provide a structure having particularly effective facilities for carrying off the heat being generated.

10 I attain this object by the structure hereinafter described, reference being had to the drawings, wherein—

Fig. 1 is a vertical axial sections, taken at 1—1 of Fig. 3, through a motor embodying 15 my invention.

Fig. 2 is an elevation of the motor.

Fig. 3 is a transverse section taken at 3—3 of Fig. 1.

20 Fig. 4 is a transverse section taken at 4—4 of Fig. 2.

Similar numerals refer to similar parts throughout the several views.

In the embodiment of my invention herein shown and described the armature core 10 is composed of a plurality of laminæ 11. Coils 12 are contained in apertures 13 of the core and extend beyond the core at both ends, forming the winding heads 14 and 16. Leads 17 emanate from the front winding 30 head 14 and commutator segments 18 are attached to the leads. An end protecting plate 19 is located at some distance from the ends of the segments.

35 All of these parts are held in their respective positions by a single mass 21 of insulation, preferably of a kind having as high thermal conductivity as may be obtained, molded in situ. This mass of insulation extends between and about the segments, penetrates the innermost recesses of the winding and fills the interstices between the several turns thereof.

40 The outer portion of the insulation mass 21 forms a complete covering 22 over the winding, and, at intervals, fins 23 extend radially outward from the covering. The fins 23 serve a twofold purpose, the first being to provide an increased area over which the heat drawn from within the mass may be 45 distributed, and the second being to act as

fan blades to move air rapidly over the heated areas.

50 Since the fins 23 are integral parts of the insulation mass 21, and since this mass extends in one continuous piece into the innermost recesses of the coils, through, between and about the individual turns thereof, and between and about the commutator segments, there is naturally provided a continuous path through the mass whereby heat is conducted 55 from the innermost turns of the winding and from the commutator segments to the surfaces of the fins as well as to the surfaces of the covering between the fins, and as the armature rotates the fins move sufficient air 60 over themselves and over the spaces between them to carry away the heat brought to these 65 surfaces.

65 The field core 24 composed of laminæ 26 has a series of winding apertures 27 around its inner diameter. Coils 28 are wound into apertures 27 and extend beyond the core at both ends, forming the coil heads 29 and 31. A mass 32 of insulation, preferably of the same kind contained in the mass 21 which forms the armature covering, is molded about the core 24 and coils 28 in the form of a hollow housing adapted to surround the 70 armature structure.

75 Coils 28 are arranged in two groups 33 and 34 (see Fig. 4) to provide a bipolar field winding, and this leaves spaces between the two groups for the openings 36. Of course in a multipolar field a greater number of coil groups, and consequently a greater 80 number of openings 36, will be had. Openings 36 are opposite the fins 23 of the armature and therefore provide outlets for the current of air moved by the fins when the armature rotates.

85 A bearing head 37 carries two spaced apart bearing bushings 38 in which the armature shaft 39 rotates, the armature being held on the shaft by the nut 41. Air inlet openings 42 in the bearing head 37 and air inlet openings 43 in the housing 32 admit air to the interior of the motor and to the inner ends 90 of the fins, so that during rotation of the armature air is drawn in at openings 42 and 43 and discharged from openings 36.

Since the mass 32 of insulation which forms the field housing also penetrates the turns of the field winding, heat from the interior of the field winding is rapidly distributed throughout the mass, so that currents of air, passing rapidly through openings which are near the winding in the mass, serve to rapidly remove the heat being generated.

Having described my invention, I claim:

1. In a dynamo electric machine, a rotatable element comprising a winding and an integral mass of insulation of high thermal conductivity extending into the winding between the turns thereof, forming a covering thereover, and extending outwardly beyond the covering to form a series of circumferentially spaced apart fins.

2. In a dynamo electric machine, an armature comprising a winding, a plurality of commutator segments attached to said winding, and an integral mass of insulation of high thermal conductivity extending into the said winding between the turns thereof and forming a covering thereover, and extending between and about the said segments, and outwardly from the said covering to form a series of circumferentially spaced apart fins.

3. In a dynamo electric machine, an armature comprising a magnetizable core having winding apertures, coils in said apertures and extending beyond the ends of the core, leads emanating from said winding, commutator segments attached to said leads, and an integral mass of insulation of high thermal conductivity extending between about said segments, into the said winding between the turns thereof and forming a covering thereover, and extending outwardly from said covering at each end of the core to form a series of circumferentially spaced apart fins.

4. The combination of a structure such as is defined in claim 1 and a stationary element surrounding said rotating element having openings communicating with the inner ends of said fins and openings communicating with the outer ends of said fins.

5. The combination of a structure such as is defined in claim 1 and a stationary element comprising a second winding and a mass of similar insulation penetrating and covering said second winding and forming a hollow housing to contain said armature with openings extending radially outward beyond said fins through the said wall of said housing and passing near the said second winding.

6. In an electromagnetic structure, coils comprising a plurality of turns of insulated wire, and an integral mass of insulation of high thermal conductivity extending into the coils between the turns thereof and forming a covering thereover, and extending outwardly beyond the covering and there forming a series of spaced apart fins.

7. In the rotatable element of a dynamo electric machine, coils comprising a plurality of turns of insulated wire, and an integral mass of insulation of high thermal conductivity extending into the coils, between the turns thereof and forming a covering thereover and extending outwardly beyond the covering and there forming a series of spaced apart fins, said fins being so positioned as to serve the purpose of fan blades for moving a current of air over the outer surfaces of the insulation body.

In testimony whereof I affix my signature.

VINCENT G. APPLE.
